CLAIM

The ornamental design for a trifold solar panel, as shown and described.

DESCRIPTION

FIG. 1 is a front perspective view of a trifold solar panel in a partially folded configuration;

FIG. 2 is a front view of the trifold solar panel shown in FIG. 1;

FIG. 3 is a back view of the trifold solar panel shown in FIG. 1;

FIG. 4 is a left side view of the trifold solar panel shown in FIG. 1;

FIG. 5 is a right side view of the trifold solar panel shown in FIG. 1;

FIG. 6 is a top view of the trifold solar panel shown in FIG. 1;

FIG. 7 is a bottom view of the trifold solar panel shown in FIG. 1;

FIG. 8 is a front perspective view of the trifold solar panel shown in FIG. 1 in a non-folded configuration;

FIG. 9 is a front view of the trifold solar panel shown in FIG. 8;

FIG. 10 is a front view of the trifold solar panel shown in FIG. 8;

FIG. 11 is a left side view of the trifold solar panel shown in FIG. 8;

FIG. 12 is a right side view of the trifold solar panel shown in FIG. 8;

FIG. 13 is a top view of the trifold solar panel shown in FIG. 8; and,

FIG. 14 is a bottom view of the trifold solar panel shown in FIG. 8.

The broken lines shown represent unclaimed subject matter and form no part of the claimed design.
